CLAIM

The ornamental design for a beta blocker demonstration
housing or the like, as shown and described.

DESCRIPTION

FIG. 1 is an isometric view of a beta blocker demonstration
housing or the like showing my new design with
the cover open and the stand in an extended position,
the legible matter is sketchily depicted for ease of illus-
tration;

FIG. 2 is an isometric view thereof with the cover
closed;

FIG. 3 is an isometric view thereof with both the cover
and the stand in a closed position;

FIG. 4 is a front end elevation of the housing with both
the cover and side flap and the stand in a closed position;

FIG. 5 is a front end elevation of the housing with the
cover open and a battery pack area exposed;

FIG. 6 is a top plane view of the housing with the cover

open showing details of the display area;

FIG. 7 is a bottom view of the housing of FIG. 3;

FIG. 8 is a side elevation of the housing taken from the

right side of FIG. 3, with the stand slightly open;

FIG. 9 is another embodiment wherein a handle is pro-
vided on the left side of FIG. 3;

FIG. 10 is a back elevation of the housing with both the
cover and the stand in a closed position; and

FIG. 11 is a back view of the housing with the stand in

an open position.
